(57) **CLAIM**

The ornamental design for an HDMI connector, as shown and described in the accompanying drawings.

DESCRIPTION

FIG. 1 is a perspective view of an HDMI connector, in accordance with the present invention.

FIG. 2 is a rear view of an HDMI connector, in accordance with the present invention.

FIG. 3 is a front view of an HDMI connector, in accordance with the present invention.

FIG. 4 is a side view of an HDMI connector, in accordance with the present invention.

FIG. 5 is an opposing side view of an HDMI connector, in accordance with the present invention.

FIG. 6 is an end view of an HDMI connector, on an enlarged scale as compared to the other figures, in accordance with the present invention; and,

FIG. 7 is an opposing end view of an HDMI connector, on an enlarged scale as compared to the other figures, in accordance with the present invention.

The broken lines showing the environment in the Figures are for illustrative purposes only and form no part of the claimed design.
